BLENDER JAR

Monte L. Levin, New York, N.Y., assignor to Dynamics Corporation of America, Waring Products Division, New Hartford, Conn., a corporation of New York

Filed Dec. 2, 1968, Ser. No. 14,735

Term of patent 14 years

Int. Cl. D7—05

U.S. Cl. D89—1

FIG. 1 is a perspective view of a blender jar showing my new design;

FIG. 2 is a top plan view thereof; and
FIG. 3 is a bottom plan view thereof.

I claim:

The ornamental design for a blender jar, as shown.
